CLAIM

The ornamental design for an animal helmet, as shown and described.

DESCRIPTION

FIG. 1 is a perspective view of an animal helmet, showing my design.

FIG. 2 is an another perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a cross-sectional view of the animal helmet of FIG. 1, taken along section line 9-9 as depicted in FIG. 5; and, FIG. 10 is a perspective view of the animal helmet in condition for use.

The broken lines in FIG. 10 depict environmental subject matter and form no part of the claimed design.

1 Claim, 10 Drawing Sheets
